SWAB

Filed May 15, 1929

FIG. 1.

HARVEY R. STANDLEE.

Inventor

By Tom J. Roman.

Attorney

UNITED STATES PATENT OFFICE

HARVEY R. STANDLEE, OF TULSA, OKLAHOMA, ASSIGNOR OF ONE-FOURTH TO PAUL ARBON COMPANY, OF TULSA, OKLAHOMA

SWAB

Application filed May 15, 1929. Serial No. 363,266.

This invention relates to oil field equipment and more particularly to a device designed for the purpose of cleaning and swabbing the interior of the casing in a well.

This device is called a swab.

Much difficulty has been experienced with the present day swabs due to the fact that they operate under very heavy pressures at times and much lighter pressure at other times. However, when the swab is in operation the expansible part or parts should snugly fit against the interior wall of the casing regardless of the pressure.

Another disadvantage of some present-day swabs is the fact that the rubber packing thereon not only wears out quickly but is difficult to replace.

It is the purpose of my invention to create a swab which will operate extremely satisfactory under a wide range of pressures and which will reduce wear upon its packing to a minimum.

I accomplish the above by using two different kinds of packing. My upper packing consists of canvas or rubber or the like and it is very stiff and the packing below this is rather flexible. The upper packing fits snugly against the casing and carries most of the pressure due to the column of fluid which is above the swab. The fluid which leaks past the stiff upper packing is carried by the flexible packings underneath. The lowest packing is not quite as flexible as the centrally situated packing.

Thus, the stiff upper packing rides against the casing and takes or carries some of the pressure of the fluid above the swab which would otherwise press inwardly upon the flexible packing just below. Hence, the difference in pressure between the inside and the outside of the flexible packing is increased with the result that very little fluid will leak past this flexible packing.

The pressure is likewise held off of the outside of the lower flexible packing by both

the flexible packing thereabove and the stiff packing. Thus the difference in pressure between the inside and outside of this last mentioned packing is even greater than that of the previously referred to packing and 50 hence this lower packing cup is made slightly thicker and stiffer.

Another advantage which I obtain is the readiness with which the worn out rubber packing or the like may be renewed due to 55 the inner taper of the collars.

Briefly described my invention consists of an integral hollow tube having a series of increasing diameters whereby all of the several packing and locking units may be successively placed on or removed from its lower end. Obviously, my integral structure has a maximum of strength with the minimum of material as there are no joints whatsoever. Furthermore, it will be appreciated as the description proceeds that the point of greatest strain is at the top of the packing unit and it is at this point that the hollow body member is the thickest. 60 65

After the several packing units and their locking means are placed in position upon the hollow body member my novel valve is threadedly engaged at the bottom end thereof. This is a one-way valve and its structure is disclosed in my Patent # 1,719,028, 70 75 filed Aug. 26, 1926, entitled Swab release mechanism.

The upper end of the circular hole in the body member terminates in a slot which passes through the wrench square and thus I utilize this flat surface for two purposes. That is to say, by drilling this slot through the flat sides of the wrench square not only is the drilling operation shortened but the path traveled by the fluid through the swab is shortened and rendered less tortuous. The body of the swab can be made shorter and no space other than the wrench square is required for the openings which permit 80 85 90

the fluid to pass from the interior to the exterior of the swab.

Other objects and advantages reside in the special construction, combination and arrangement of the various elements forming the invention as more fully hereinafter described and claimed, reference being had to the accompanying drawings forming part thereof, wherein;

10 The figure is a side view of my swab, parts being broken away in order to facilitate the showing.

Similar numerals represent similar parts throughout the several views.

15 Referring now to the drawing, numeral —10— indicates the main body or mandrel of my swab. The main body or mandrel is preferably forged from high grade steel and it has the usual tapered and threaded portion —11— at its upper end, by which it is attached to the usual string of tools as is well known to those skilled in this art.

20 A short distance below the threaded part —11— are formed flat surfaces —12— and —13— thereby furnishing an ordinary wrench square and a slot or opening —14— passes directly through the body from one flat surface to the other.

25 The slot —14— connects with the hole —15— which runs longitudinally of the main body member. The hole —15— and the slot —14— provide a passageway for the fluid upwardly as the swab is gravitated downwardly into the well.

30 A shoulder —16— is formed just below the slot or opening —14— and a cylindrical seat —17—, with a threaded portion —18—, is formed just below the shoulder. Thus, the impregnated canvas and rubber packing —20—, with the disc plate —21— as a follower, is held tightly against the shouldered portion —16— by means of an ordinary lock nut —22—.

35 Just below the lock nut —22— the diameter of the body portion is reduced to form the surface —23— with a threaded portion —24— and an inverted cup-shaped member —25— formed of a bottom part —26—, with a hole therein, and a tapered flange —27—, is placed against the shoulder —28—. Another similar cup member —25— is uprightly placed below the inverted cup member and thus a seat is formed for my flexible rubber packing.

40 45 50 55 60 65 65 As shown, my packing consists of a bulged cylindrical shaped flexible body —30—, preferably of rubber, and tapered end portions —31— and —32— which snugly fit into the cups —25—. Lock nuts —33— and —34— are threadedly engaged upon the threaded portion —24— and provide means for placing the rubber packing —30— under compression as well as retaining it in place. Additional pressure is obtained on the inside of the packing —30—,

when under actual working conditions, by boring holes —35— through the body just behind the bulged portion of the flexible packing. These holes allow the fluid to freely enter behind the packing and push it outwardly but the stiff upper packing hinders the fluid pressure from immediately reaching the outer side of this flexible packing and hence a difference in pressure is obtained. This outwardly directed pressure maintains a desirable tight fit between the flexible packing and the casing.

A shoulder —40— is formed just below the threaded portion —24— and cups —41— hold the rubber —42— in place and are in turn held in place by the lock nuts —43— and —44— threadedly engaged upon the threaded portion —45—. A hole —46— allows the fluid to pass behind the rubber —42— and add to its outward pressure when in operation.

As previously set forth the stiff packing prevents the fluid pressure from reaching the outside of the upper flexible packing and allows it only on the inside thereby causing it to expand. Similarly, or rather in increasing fashion, the stiff packing and the upper flexible packing both tend to prevent fluid pressure from reaching the outside of this lower cup and hence its inner pressure causes it to press snugly against the walls of the casing in which it is being operated.

The threads —45— also provide means for holding the neck —51— of the valve —50— rigid in place at the bottom of the mandrel or body part. This is a one-way valve and it allows the fluid to pass upwardly as the swab is being lowered into the well.

Although a particular embodiment of the invention has been illustrated and described in order to comply with the terms of the patent statutes, it is not intended that the invention shall be limited to said particular embodiment since the invention may be applied to other forms without departing from its spirit.

I claim:

1. A swab consisting of a substantially cylindrical integral body of successively increasing diameters relative to one end thereof and a squared portion thereon near the other end; threaded portions on the several stepped portions adjacent the shoulders therebetween, extremely stiff packing on the portion closest to the squared portion; means for holding or locking it in place; other packing on the adjacent portion and means to hold it in place.

2. A swab comprised of a body member having a hole therethrough, heavy stiff packing encircling the swab near its top, flexible packing encircling the swab below its top, said body member having an opening leading from its interior hole to a

point behind the last mentioned packing whereby the fluid load on the swab will cause it to expand.

3. A swab as set forth in claim 1 but also having an additional flexible packing, somewhat thicker and stiffer than the flexible packing previously mentioned, encircling the swab below the first mentioned packing, said body member having an opening leading from its interior hole to a point behind the thicker and stiffer flexible packing.

In testimony whereof, I affix my signature.

HARVEY R. STANDLEE.

CERTIFICATE OF CORRECTION.

Patent No. 1,743,937.

Granted January 14, 1930, to

HARVEY R. STANDLEE.

It is hereby certified that error appears in the printed specification of the above numbered patent requiring correction as follows: Page 3, in claim 3, first line, for "claim 1" read "claim 2"; and that the said Letters Patent should be read with this correction therein that the same may conform to the record of the case in the Patent Office.

Signed and sealed this 25th day of March, A. D. 1930.

(Seal)

M. J. Moore,
Acting Commissioner of Patents.
